Primary Examiner — Darlington Ly*Assistant Examiner* — D. Ryan Tisdale(74) *Attorney, Agent, or Firm* — Clements Bernard Walker; Christopher L. Bernard(57) **CLAIM**

The ornamental design for wheel rim, as shown and described.

DESCRIPTION

FIG. 1 is a front perspective view of a wheel rim.

FIG. 2 is a rear perspective view of the wheel rim of FIG. 1.

FIG. 3 is a front elevation view of the wheel rim of FIG. 1. FIG. 4 is a left side elevation view of the wheel rim of FIG. 1.

FIG. 5 is a rear elevation view of the wheel rim of FIG. 1. FIG. 6 is a top plan view of the wheel rim of FIG. 1; and, FIG. 7 is a bottom plan view of the wheel rim of FIG. 1.

The broken lines in the drawings illustrate portions of the wheel rim that form no part of the claimed design.

1 Claim, 7 Drawing Sheets(56)
